UNITED STATES PATENT OFFICE.

PETER N. SWANSON, OF GALVA, ILLINOIS.

FARM-DERRICK.

SPECIFICATION forming part of Letters Patent No. 591,612, dated October 12, 1897.

Application filed January 20, 1897. Serial No. 619,849. (No model.)

To all whom it may concern:

Be it known that I, PETER N. SWANSON, a citizen of the United States, residing at Galva, in the county of Henry and State of Illinois, have invented certain new and useful Improvements in Farm-Derricks; and I do hereby declare the following to be a full, clear, and exact description of the invention, such as will enable others skilled in the art to which it appertains to make and use the same.

This invention has reference to a novel construction in a farm-derrick, the object being to provide a device of this character which can be conveniently set up in different places and which can be used for removing and replacing wagon-tops or hay-racks.

The invention consists in the features of construction hereinafter fully described and specifically claimed.

20 In the accompanying drawings, forming a part of this specification, Figure 1 is a perspective view of a derrick constructed in accordance with this invention. Fig. 2 is a top plan of the same.

25 The said derrick can be supported from any suitable support, such as a post or the trunk of a tree, as indicated by 1, and upon the hooks 2 fastened thereto. The said derrick consists of an upright 3, having tapering sides, so that

30 it fits between the top pieces 4 and the braces 5. The said top pieces 4 are fastened together at an angle and are tapered at their rear ends to make a tapering joint, and the lower ends of the braces 5 are similarly made. The said

35 tapering upright 3 is situated at the crotch made by the top pieces 4 and braces 5 and is suitably bolted to said parts. Straps 6 are fastened to the rear ends of the top pieces 4 and braces 5 and form hinges to receive the

40 hooks 2. The braces 5 diverge upwardly and outwardly and meet the diverging ends of the top pieces 4, to which they are secured, and are further braced by a cross-piece 7. The said cross-piece 7 is provided near each end

45 thereof with pulleys 8, which fasten to the lower face of the braces. Near their lower ends is a winding-drum 9 and a ratchet-wheel and ratchet for holding the same. Between the winding-drum and the upper end of the

derrick is a cross-support 11, carrying the 50 guide-pulleys 12, and cords or cables 13 are fastened to the winding-drum 9 and are guided by the pulleys 12 to the pulleys 8, over which they pass, and then around the block and tackle in the manner shown. The said 55 blocks are provided with toggle-hooks 14, which consist of two pivoted jaws 15, having the extension 16 of said jaws pivoted to two links 17, which links in turn are pivoted to the eye or loop 18. The said eye or loop 18 60 is fastened to the block in the usual manner.

In use the wagon is driven below the outer end of the derrick and the cords are unwound sufficiently to allow the hooks to descend and when extended to engage the sides of the 65 hay-rack or wagon-top. It is seen, therefore, that when the cords are wound up by a pull upon the upper end of the tackle the hooks are held in engagement with the wagon-top, whereby the latter can be lifted from the 70 wagon, after which the derrick can be moved to one side to allow the hay-rack or wagon-top to be deposited upon the ground. It is therefore noted that the wagon-top can be as 75 easily replaced, and that, furthermore, it can be done by one person.

Having thus described my invention, what I claim as new, and desire to secure by Letters Patent, is—

A derrick consisting of two top pieces 80 fastened together at an angle and having their joining ends tapering, a strap around said tapering end, inclined converging braces having their lower ends tapered and joined, a strap around the lower ends of said braces, 85 an angular upright fastened between the crotches of said top pieces and braces, a cross-piece fastened to the outer ends of said top pieces and braces, a winding-drum upon said braces, and a cross-bar having guide-pulleys 90 at the upper and outer ends of said braces.

In testimony whereof I have signed this specification in the presence of two subscribing witnesses.

PETER N. SWANSON.

Witnesses:

NEWMAN M. HENRY,

JOHN A. BURG.
